UNITED STATES PATENT OFFICE.

JOHN L. MOHUN, OF NEW YORK, N. Y.

CAR ROOF.

Application filed February 21, 1920. Serial No. 360,534.

To all whom it may concern:

Be it known that I, JOHN L. MOHUN, a citizen of the United States, and a resident of the city of New York, in the county of Kings and State of New York, have invented a new and useful Improvement in Car Roofs, of which the following is a specification.

This invention relates principally to car roofs of the rigid all steel riveted type, wherein heavy gage self-supporting roof sheets extend from eaves to eaves of the car and have upstanding flanges at their side margins riveted together and covered by seam covers or outside carlines, the seam covers and the sheet flanges covered thereby being rigidly secured together from eaves to eaves. With the above type of roof, all of the rivets, which secure the seam flanges together, are exposed and there is a tendency for the rivets to work loose, thus permitting water to enter the seam and cause the roof to leak. Leakage around the rivets is also sometimes caused by the workmen not driving the rivets as tight as they should be driven. The principal object of the present invention is to prevent leakage around the rivets which secure the seam flanges and to obtain other advantages hereinafter appearing. The invention consists in the hereinafter described seam construction and in the arrangements and combinations of parts hereinafter described and claimed.

In the accompanying drawings, wherein like symbols refer to like parts wherever they occur,

Fig. 1 is a fragmentary plan view of a car roof embodying my invention, parts being broken away to more clearly illustrate the invention;

Fig. 2 is an enlarged vertical section taken crosswise of the roof on the line 2—2 in Fig. 1;

Fig. 3 is an enlarged detail cross-section taken through the side plate adjacent to a seam on the line 3—3 in Fig. 1;

Fig. 4 is a vertical cross-section through one of the seams, the section being taken longitudinally of the car at the ridge on the line 4—4 in Fig. 2;

Fig. 5 is a vertical cross-section through one of the seams, the section being taken midway between the eaves and ridge of the car on the line 5—5 of Fig. 1;

Fig. 6 is a horizontal section through one

of the securing bolts on the line 6—6 in Fig. 3;

Fig. 7 is a view similar to Fig. 5, showing a modified form of seam, the seam flanges being shown in contact from top to bottom and the base flanges of the seam cover being shown spaced above the sheets;

Fig. 8 is a cross-section through the ridge portion of a seam, showing a modified form of running board saddle and fillers located in the spaces between the sheet flanges and the outside carline; and

Figs. 9, 10, 11 and 12 are detail sections, taken at the ridge, showing my invention in connection with different types of inside carlines.

In Figs. 1 to 6 of the drawings, the roof is shown applied to a car having metal Z-bar side plates 11, but the roof can be applied to other types of cars having wooden or metal side plates of various cross-sections. The metal roof sheets 12 are arranged cross-wise of the car, extending from eaves to eaves preferably in the form of curves or arcs, and are self-supporting. The side margins of the roof sheets are turned up forming side flanges 13. The side flanges 13 of each sheet are inclined outwardly and upwardly from the body portion thereof and the upper marginal portions of said flanges are disposed at right angles to the plane of the body of the sheet. The sheets are placed side by side and the contacting upper marginal portions of the side flanges, except for a distance on each side of the ridge, are secured together by rivets 14. Thus, the seam flanges constitute stiffening ribs and enable the sheets to sustain such loads to which they are subjected in ordinary operation. The side seam flanges are preferably shown gradually decreasing in height from the ridge to a point near the eaves where, from thereon, their height decreases more rapidly, the flanges merging into the plane of the sheet at the eaves ends thereof. This provides the seam flanges with a sufficient vertical stiffness at the ridge to support the roof load and provides a maximum clearance at the eaves. The eaves ends of the roof sheets are turned down over the web portions of the side plates in the form of vertical depending flanges 15.

The side flanges of the roof sheets, together with the rivets which secure them together, are covered throughout their length by seam covers or outside carlines 16 of

substantially inverted U-shape section. These outside carlines are of a width sufficient to straddle the wide base portions of the seam flanges and are provided with the 5 lateral base flanges 17, which extend over the body portion of the sheets on opposite sides of the seam. These outside carlines gradually decrease in height from the ridge towards the eaves in a manner corresponding 10 to the decreased height of the seam flanges. The eaves ends of the outside carlines are closed by abruptly decreasing their height from a point near the eaves to their ends where they merge into the plane of 15 the lateral flanges 17 of the outside carline and are turned down in the form of the vertical end flanges 18.

A series of equally spaced anchor and 20 flashing members 19 are secured to the top flanges of the side plates 11 in alignment crosswise of the car. These anchor and flashing members are in the form of angle brackets whose horizontal flanges are riveted to the upper flanges of the side plates and 25 whose vertical flanges project downwardly along the side of the web portions of the side plates and are riveted or otherwise secured thereto. The horizontal flanges of the bracket members are provided with up- 30 standing vertical web portions 20 which extend between the upstanding seam flanges of the roof sheets and are covered by the closed ends of the outside carlines. The outside carlines and the seam flanges are secured to the web portions 20 of the anchor members by means of rivets.

At the ridge, the side walls of the outside carlines are pressed inwardly towards each other as at 21 to closely embrace the seam flanges. The depressed portions of the outside carlines are secured to the roof sheet flanges by means of rivets 22. These rivets also form means of securing the vertical flange of an angle shaped running board 45 saddle 23 to the seam covers or outside carlines. Running boards 24 are supported on the horizontal flange of the running board saddles and are secured thereto by bolts.

The depending eaves flanges 15 of the roof 50 sheets and the depending eaves flanges 18 of the outside carlines are secured to the vertical web portions of the side plates by means of collar bolts 25. These collar bolts are shown and described in my Patent No. 55 1,069,565, dated August 5, 1913 and extend through the depending flanges of the roof sheets and have integral collar portions 26 located between the inner surface of the eaves flanges 15 of the roof sheets and the 60 outer surface of the web portion of the side plates. The outer ends of the bolts are provided with nuts 27 which clamp the eaves flanges of the roof sheets to the collars of the bolts. The collars of the bolts are drawn 65 tightly against the side plates by means of

nuts 28 threaded on the inner end of the bolts. This arrangement prevents the water from following the bolts and leaking into the car. The bolts which secure the outside carline to the side plates are located below 70 the lower edges of the vertical flanges of the anchor members 19 and pass through the downturned flanges 15 of the roof sheets and the downturned flanges 18 of the seam covers.

Fig. 7 illustrates a modified form of seam. In this construction, the base flanges 17^a of the outside carline 16^a are shown spaced above the body portion of the sheets 12^a. With this arrangement the outside carline 80 is clear of the sheets and the seam flanges 13^a throughout their length, except for a distance at the ridge where the outside carline is secured to the seam flanges in the manner previously described. This spacing 85 of the carline above the sheets affords a ventilating space and prevents the accumulating of moisture, cinders and dirt in the seam, causing the sheets to rust and corrode.

In Fig. 8 the seam is shown provided with 90 fillers or spacers 31. These fillers are arranged between the inner walls of the outside carline and the adjacent side faces of the seam flanges at the ridge. The fillers are held in place by the rivets which connect 95 a running board saddle 32 to the carline and the carline to the roof sheet. The running board saddle is of T-shaped section and its horizontal flange portions, which support the running board, extend for a distance 100 on opposite sides of the carline to overhang the rivets and thus protect the same from the weather.

In Fig. 7, as well as in Fig. 8, the seam flanges, below the securing rivets, abut instead of being spread apart as shown in Figs. 1 to 6. This arrangement permits the securing rivets to be located closer to the plane of the sheets and prevent spreading apart of the sheets at their margins, thus better enabling the sheets to resist horizontal stresses.

Figs. 9 to 12 show my form of seam cover or outside carline in connection with different types of inside carlines. All of these designs show means for fastening the inside 115 carlines to the roof sheets, thus tying the roof sheets and the seam covers to the car substructure at the ridge.

In Fig. 9 the inside carline 33 is a pressed steel member of U-shaped section and has 120 lateral flanges 34 at its top for supporting the roof sheets 12. The roof sheets are secured to the side plate in the hereinbefore described manner. At the ridge, the carline 33 is provided with a short member 35 of T- 125 section whose base flanges 36 are riveted or otherwise secured to the lateral top flanges 34 of the carline. The web portion of the member projects upwardly between the seam flanges 13 of the roof sheets. At this 130

point the sides of the outside carline 16 are brought together to embrace the seam flanges 13 and, the outside carline and the seam flanges, together with the running board saddle, are secured to the web portion of the ⁵ T member by means of rivets.

In Fig. 10, the seam is shown in connection with a carline 37 of T-section. This carline extends from side plate to side plate ¹⁰ and the seam flanges 13 on opposite sides of its vertical web portion are secured to said web portion by rivets. At the ridge, the outside carline 16, which covers the securing rivets, has its side walls depressed ¹⁵ to closely embrace the seam flanges. The depressed walls of the outside carline together with the running board saddle is secured to the vertical web portion of the carline by rivets.

²⁰ In Fig. 11, the seam is shown in connection with a built up carline comprising angle members 38. A short member 39 of T-section is secured to the top of the angle members of the carline at the ridge. The ²⁵ outside carline 16 and seam flanges 13 are secured to the web portion of the ridge member 39 of the carline 38 in the same manner as in Figs. 7 and 8.

In Fig. 12, the seam is shown in connection with a slightly modified form of built up carline. This carline comprises angle members 40 whose vertical flanges are disposed back to back. At the ridge, a plate ³⁵ 41 is arranged between the vertical flanges of the angle members 40 of the carline. This plate extends upwardly between the seam flanges 13 and its upper surface terminates flush with the upper edges thereof. The ⁴⁰ seam flanges of the sheets together with the depressed side wall of the outside carline 12 are riveted or otherwise secured to the plate 41.

With the construction described, the roof seams, which may be of any desired type, ⁴⁵ as well as the rivets which secure the seam flanges together, are covered by the outside carline, thus protecting the joints and the rivets from the weather and resulting in a water-tight roof. The only exposed rivets ⁵⁰ are the rivets which connect the sheet flanges to the carlines and which also connect the running board saddle to the seam cover. These last mentioned rivets are fairly well protected by the running boards and, if desired, the saddle of T-section, such as shown ⁵⁵ in Fig. 8, may be used to further protect these rivets from the weather. The covering of the rivets which secure the seam flanges by the outside carline permits the ⁶⁰ use of cold-driven rivets.

It is noted that the roof sheets are supported at the ridge by the outside carline while at the eaves, the sheets, as well as the outside carlines, are rigidly secured to ⁶⁵ the side plates of the car. As shown in

Figs. 9 to 12, the roof is adapted for use in connection with roofs having inside carlines and purlins with slight modification.

The hereinbefore described arrangement is considered only as an example and as ⁷⁰ being the one most adapted to the style of roof shown. Therefore, I do not wish to be limited to the exact form of joint or to the exact eaves construction shown, as the invention is applicable to cars having various forms of roof joints and eaves constructions.

What I claim is:

1. A car roof comprising roof sheets extending from side plate to side plate and having upturned side marginal flanges rigidly secured together to form joints, an outside carline covering each of said joints and the securing means therefor, said carline being out of contact with said joints and ⁸⁰ being secured to said roof sheets only in the region of the ridge, said roof sheets and said outside carline being rigidly secured to said side plates at their eaves ends.

2. A car roof comprising roof sheets extending from side plate to side plate and having upturned side flanges arranged side by side and rigidly secured together throughout their length to form joints, an outside carline covering each of said joints ⁹⁰ and the securing means therefor, said carline being out of contact with said joints and said roof sheets and being secured to said roof sheets only in the region of the ridge, said roof sheets and said carline being rigidly secured to said side plates at ⁹⁵ their eaves ends, and a running board saddle supported by said carline independently of said roof sheets.

3. A car roof comprising roof sheets extending from side plate to side plate and having upturned side flanges rigidly secured together to form joints, and an outside carline of inverted U-section arranged above said joints and covering the joints ¹⁰⁵ and the securing means therefor, the top and side walls of said carline being out of contact with said joints except for a distance on each side of the ridge where the side walls of said seam cover are depressed ¹¹⁰ to engage the upturned side flanges of said sheets and are rigidly secured thereto, said roof sheets and said carline having their eaves ends rigidly secured to said side plate.

4. A car roof comprising roof sheets extending from side plate to side plate and having upturned side flanges rigidly secured together to form joints, and an outside carline of inverted U-section arranged above said joints and covering the joints and the ¹²⁰ securing means therefor, the top and side walls of said carline being out of contact with said joints except for a distance on each side of the ridge where the side walls of said seam cover are depressed to engage ¹²⁵ to

- the upturned side flanges of said sheets and are rigidly secured thereto, said roof sheets and said carline having their eaves ends rigidly secured to said side plate, and a running board saddle rigidly secured to said carline and supported thereby independently of the roof sheets.
5. A car roof comprising roof sheets extending from side plate to side plate and having upturned side flanges rigidly secured together to form joints, and an outside carline of inverted U-section arranged above said joints and covering the joints and the securing means therefor, the top and side walls of said carline being out of contact with said joints except for a distance on each side of the ridge where the side walls of said seam cover are depressed to engage the upturned side flanges of said 10 sheets and are rigidly secured thereto, said roof sheets and said carline having their eaves ends rigidly secured to said side plate, and a running board saddle rigidly secured to said carline and supported thereby independently of the roof sheets, said running board saddle having portions adapted to support running boards, said portions overhanging the means for securing the running board saddles to the carline to protect said securing means from the weather.
- 15 6. A car roof comprising roof sheets extending from side plate to side plate and having upturned side flanges rigidly secured together to form joints, and an outside carline of inverted U-shaped section with outwardly projecting flanges along the bottom edges of its side walls arranged over each of said roof joints, the eaves ends of said roof sheets and said carline being rigidly secured to said side plates and said carline being secured to said roof sheets only in the region of the ridge.
- 20 7. A car roof comprising roof sheets extending from side plate to side plate having upturned side flanges rigidly secured together to form joints, and an outside carline of inverted U-shaped section with outwardly projecting flanges along the bottom edges of its side walls arranged over each of said roof joints, said flanges being spaced above the roof sheets, the eaves ends of said roof sheets of said carline being rigidly secured to said side plates and said carline being secured to said roof sheets only in the region of the ridge, and a running board saddle supported on said carline independently of the roof sheets.
- 25 8. A car roof comprising roof sheets extending from side plate to side plate having upturned side flanges rigidly secured together to form joints, an outside carline of inverted U-shaped section with outwardly projecting flanges along the bottom edges of its side wall arranged over each of 30 said roof joints, the top and side walls of said carline being spaced from the roof joints on opposite sides of the ridge and the outwardly projecting flanges thereof being spaced above the roof sheets, the eaves ends of said roof sheets of said carline being rigidly secured to said side plates, the side walls of said carline being depressed for a distance at the ridge and rigidly secured to said joints, said joints and said carlines being otherwise unconnected, and a running board saddle supported on said carline independently of the roof sheets.
- 35 9. A car roof comprising roof sheets extending from side plate to side plate and connected along their side margins by rigid joints, and an outside carline of substantially U-shaped section covering each of said joints, the side walls of said carline being spaced away from said joints and said carline being unsecured to said joints except for a distance on opposite sides of the ridge, and spacers arranged between the side walls of the carline and the joints at the ridge, said spacers being adapted to fill the space between the side walls of the carline and the joints and being secured in position by the means for securing the carline at the ridge portion of the joint.
- 40 10. A car roof comprising a substructure having an upwardly extending portion at the ridge, roof sheets extending from eaves to eaves and having upturned side flanges arranged side by side and rigidly secured together to form joints, the upwardly extending ridge portion of the substructure extending between the side flanges of the sheets and being rigidly secured therebetween, and an outside carline covering the roof joints, said carline being secured to the roof sheets only at the ridge.
- 45 11. A car roof comprising side plates connected by inside carlines, said carlines having upwardly extending portions at the ridge, roof sheets extending from side plate to side plate and connected along the side margins by joints, the upwardly extending portion at the ridge of said carline extending into said joints and secured therein, and an outside carline covering the roof joints, said outside carline being secured to the upwardly extending portion of the inside carline and being secured to said roof sheets only at the ridge.
- 50 12. A car roof comprising side plates connected by inside carlines, said carlines having upwardly extending portions at the ridge, roof sheets extending from eaves to eaves and connected along their side margins by joints, upwardly extending portions at the ridge of the carlines extending into said joints and being rigidly secured therein, and an outside carline covering the roof joints, said carline and said roof sheets having their eaves ends rigidly secured to the side plates, said outside carline being se-

cured to the upwardly extending portion of the inside carline and being unsecured to said roof sheets except for a distance at the ridge, and a running board saddle secured to said outside carline and supported solely by the same.

13. A car roof comprising inside carlines extending from side plate to side plate and having upwardly extending web portions at the ridge, roof sheets extending from side plate to side plate and having upturned side flanges arranged side by side and rigidly secured together, the web portion of said carline extending between the upstanding side flanges of said sheets and rigidly secured therebetween, and an outside carline covering the upturned flanges of the roof sheets, said outside carline being secured to the web portion of the inside carline and being unsecured to said roof sheets except at the ridge.

14. A car roof comprising inside carlines extending from side plate to side plate and having upwardly extending web portions at the ridge, roof sheets extending from side plate to side plate and having upturned side flanges arranged side by side and rigidly secured together, the web portion of said carline extending between the upstanding side flanges of said sheets and rigidly secured therebetween, said roof sheets and said outside carline having their eaves ends rigidly secured to said side plates, said outside carline covering the upturned flanges of the roof sheets, said outside carline being secured to the web portion of the inside carline and being unsecured to said roof sheets except at the ridge, and a running board saddle secured to said outside carline and supported thereby independently of said roof sheets and said inside carline.

15. A car roof comprising roof sheets extending from side plate to side plate with their eaves ends rigidly secured thereto, said roof sheets having upstanding flanges along their side margins rigidly secured together to form seams, and an anchor member secured to each side plate beneath each of said seams, said anchor member having a portion projecting upwardly between the seam flanges of the roof sheets and said seam flanges being rigidly secured thereto.

16. A car roof comprising roof sheets extending from side plate to side plate and connected along their side margins by joints, an anchor member secured to each side plate at each of said joints, said anchor member extending on opposite sides of said joint and having an upwardly projecting portion extending into said joint and rigidly secured therein.

17. A car roof comprising roof sheets extending from side plate to side plate with their eaves ends rigidly secured thereto, said roof sheets being connected along their side

margins by joints, and anchor members secured to said side plates at each of said joints, each anchor member extending on opposite sides of said joint and having an upwardly projecting portion extending into said joint and rigidly secured therein, said anchor member being adapted to support the eaves ends of said roof joint.

18. A car roof comprising roof sheets extending from side plate to side plate and connected along their side margins by joints, and an anchor member secured to said side plate beneath each of the roof joints, said anchor member extending on opposite sides of the joints, and an outside carline covering each of said roof joints, said anchor member having a portion extending upwardly into said roof joints and rigidly secured therein, said outside carline being also secured to said anchor member.

19. A car roof comprising roof sheets extending from side plate to side plate with their eaves ends rigidly secured thereto, said roof sheets being connected along their side margins by joints, an anchor member secured to said side plates beneath each of the roof joints, said anchor member extending on opposite sides of the joints, and an outside carline covering each of said roof joints and having its eaves ends rigidly secured to said side plate, said anchor member extending upwardly into the roof joint and being rigidly secured therein, said outside carline being also secured to said anchor member and to said joints at the eaves and being secured to said roof joints for a distance on each side of the ridge.

20. A car roof comprising roof sheets extending from side plate to side plate connected along their side margins by joints, said roof sheets having their ends turned down and rigidly secured to the outer faces of said side plates, and a combined anchor and flashing member secured to said side plates beneath each of said joints, said anchor member having a portion arranged between the downturned ends of the roof sheets and the side plates and having a portion provided with an upstanding web resting on the side plates, said web portion extending into the roof joints and being rigidly secured therein, and an outside carline covering each of said roof joints and having its outer ends turned down over the roof sheets and rigidly secured to said side plates, portions of said outside carline adjacent to the anchor member being rigidly secured to the web portion of the seam and the ridge portion of said outside carline being connected to said roof joints for supporting the same.

Signed at New York, New York, this 17th 125 day of February, 1920.

JOHN L. MOHUN.
